GAS TRAP

Warren C. Kimbrough, Portland, Oreg.

Application October 4, 1947, Serial No. 778,016

2 Claims. (Cl. 48—193)

1

This invention relates to improvements in gas detectors and more especially to means for providing free escapement to the atmosphere of gas leaking from gas pipes buried in and below the surface of the ground.

The invention relates to the type of gas trap shown and described in my United States Patent 2,134,050, dated October 25, 1938.

One of the principal objects of the present invention is to provide a gas trap of the character above referred to but which is more efficient in operation and of less expensive construction and one which is more convenient to install for operative engagement with underground gas pipes.

A further object of the invention is the provision of means embodied in one end wall of the trap which enables said wall to come into substantially face to face contact with the wall of the building or other structure to which it is applied; said means also serving the dual purpose of locking the trap to the pipe to prevent its displacement and also to provide an absolute seal around the pipe passing through said one end wall.

A still further object of the invention is that it may be inexpensively made of sheet metal with a minimum number of punching and forming operations and at the same time be of adequate strength to withstand the heavy loads of earth packed around and above it when installed beneath the surface of the ground.

The foregoing and other objects will appear as my invention is more fully hereinafter described in the following specification, illustrated in the accompanying drawing and finally pointed out in the appended claims.

In the drawing:

Figure 1 is a perspective view of a gas trap made in accordance with my invention and operatively engaged with an underground gas pipe shown in broken lines.

Figure 2 is a side elevation of the trap installed beneath the surface of the ground and with one of its end walls in face to face contact with a wall of a building through which the gas pipe is extended.

The gas trap of the present invention consists of a housing generally indicated at 1 and consisting of top and side walls made of a single piece of material and shaped as shown. To both ends of the housing are secured by any suitable means end walls 2 and 3. Secured to the top wall is an outlet fitting 4 in open communication with a vent pipe 5 secured to the fitting by any

suitable means. The uppermost end of the vent pipe is turned back on itself as at 6 to prevent admission of dust, or any foreign substances which would tend to obstruct the vent. The wall 3 of the trap is formed with an enlarged opening 7 to freely admit escaping gas to the interior of the trap, while the opposite wall 2 is formed with a smaller opening 8 adapted to straddle a gas pipe extending through both of said walls. 5 To secure the housing to the pipe and to prevent gas from escaping through the wall 2 around the gas pipe, I provide two overlapping closures 9 and 10 formed with semi-circular cut-outs 11 and 12 respectively, and swingably attached to the wall 2 by means of a rivet or bolt 13. When both halves are drawn together, as shown, the cut-out portions 11 and 12 snugly surround the pipe while the remaining portions of the closures completely cover the opening 8. Thus 15 any gas escaping lengthwise of the pipe is collected in the trap and directed upwardly and out to the atmosphere through the vent pipe 5. The closures also serve to lock the housing to the gas pipe to prevent accidental displacement.

20 Ordinarily gas traps are installed around a pipe below the surface of the ground by digging an opening to a level below that of the gas pipe, and the various sections of the trap are assembled around and over the pipe at the time of installing. 25 This of course requires considerable labor and manipulation of the parts into position for assembly, but with my invention the trap, being made in a single unit, need only be dropped in place over the pipe and locked and sealed at one of its ends with respect thereto, by merely closing the closures 9 and 10 into the position shown in Figure 1. Moreover, the relatively flat end wall 2 enables the trap to be placed squarely against the wall of the building to which it is applied in substantially face to face contact to prevent gas which might possibly escape from working its way to the interior of the building around the pipe through the opening through which it passes to the interior of the building.

30 40 45 While I have shown a particular form of embodiment of my invention, I am aware that many minor changes therein will readily suggest themselves to others skilled in the art without departing from the spirit and scope of the invention. 50 Having thus described the invention: what I claim as new and desire to protect by Letters Patent is:

I claim:

1. A gas trap consisting of a bottomless housing of inverted U shape in cross section closed

at one of its ends by a wall having an elongated vertical opening therein, a pair of closure plates pivoted to said wall and adapted when drawn together to seal off said opening, a pair of aligned cut-outs in said closure plates adapted to encircle a pipe extending through the housing to prevent escapement of gas through said wall about the pipe and to lock the housing to the pipe against accidental displacement, the opposite end of the housing being formed with a wall having an enlarged opening therein to straddle said pipe, a vent opening formed in the top of the housing, and a conduit in open communication with the atmosphere.

2. A gas trap consisting of a housing of inverted 15

U shape in cross section closed at one of its ends by a solid wall having an opening therein, a pair of closure plates pivoted to said wall and having semi-circular cut-outs therein to encircle a pipe extending through the housing, the opposite end of the housing being formed with a wall having an enlarged opening therein to straddle said pipe, a vent opening formed in the top of the housing, and a conduit in open communication at one of its ends with said vent opening, and its opposite end in open communication with the atmosphere above the ground.
